UNITED STATES PATENT OFFICE

164,688

FONT OF TYPE

Antonio C. Jimenez, New York, N. Y.

Application April 16, 1951, Serial No. 14,856

Term of patent 14 years

(Cl. D64—12)

To all whom it may concern:

Be it known that I, Antonio C. Jimenez, a citizen of Spain, residing in the city, county and State of New York, have invented a new, original, and ornamental Design for a Font of Type of which the following is a specification, reference being had to the accompanying drawing, forming a part hereof, in which:

Fig. 1 is a plan view of the upper case alphabet of a font of type embodying my new design;

Fig. 2 is a plan view of a portion of the alphabet in lower case embodying such design;

Fig. 2a is a plan view of the remaining portion of the lower case alphabet;

Fig. 3 is a plan view of the principal constituent geometrical figures employed in connection with the font of type illustrated in Figs. 1, 2 and 2a.

I claim:

The ornamental design for a font of type, as shown.

ANTONIO C. JIMENEZ.
